ATTORNEY

UNITED STATES PATENT OFFICE.

SAMUEL A. GARBER, OF FORTUNA, NORTH DAKOTA.

WHIP-HOLDER.

1,213,860.

Specification of Letters Patent. Patented Jan. 30, 1917.

Application filed August 16, 1916. Serial No. 115,289.

To all whom it may concern:

Be it known that I, SAMUEL A. GARBER, a citizen of the United States, residing at Fortuna, in the county of Divide and State 5 of North Dakota, have invented certain new and useful Improvements in Whip-Holders, of which the following is a specification.

This invention relates to whip holders, and particularly to devices of this character 10 which are located upon animal harness and which are capable of being actuated to whip the animal.

The primary object of the invention is to provide a device of this character capable of 15 application to the hame of the harness, and which is adapted to be actuated from the driver's position to whip the animal's back.

A still further object of the invention is to provide a device of this character which is 20 capable of being quickly and easily attached to or detached from the harness, which is composed of but few simple and inexpensive parts, all so constructed and arranged as to prevent wear, breakage or derangement of 25 the same, which is positive in operation, and which will prove thoroughly efficient in the attainment of the ends for which it is designed.

With these objects in view, together with 30 others which will appear as the description proceeds, the invention resides in the novel formation, combination and arrangement of parts, all as will be described more fully hereinafter, illustrated in the drawings, and 35 particularly pointed out in the claims.

The invention will be best understood with reference to the accompanying drawings, wherein:—

Figure 1 is an elevational view of a whip 40 holding device constructed in accordance with my invention, the same being shown as attached to a harness hame, Fig. 2 is a vertical sectional view taken upon line 2—2 of Fig. 1, Fig. 3 is similar view taken on line 45 3—3 of Fig. 1, Fig. 4 is sectional view taken on line 4—4 of Fig. 1, and Fig. 5 is a sectional view taken on line 5—5 of Fig. 1.

Referring now more particularly to the drawings, 6 indicates the base or holder, and 50 7 the whip holding device or socket. The base comprises a clamping device formed of a length of sheet metal bent upon itself as shown to provide a pair of spaced parallel leaves 8, the latter being adapted to engage 55 upon the opposite side of a harness hame as shown in Fig. 1. The extremities of the

leaves 8 are extended as shown, and are provided with registering elongated slots 9, through which a clamping bolt 10 extends, the latter being equipped with a wing nut 60 11 to facilitate the ready application of the bolt to the base. By this means it is obvious that the base may be readily applied to hames of various widths and thicknesses.

The lower portion of one of the leaves 8 65 is rolled throughout its length as shown, the rolled portion forming a barrel 12 for the accommodation of a bolt or pin 13. To prevent the bolt or pin rotating within the barrel 12, a cotter pin 14 may be extended 70 through registered apertures in the barrel and an opening extending transversely of the bolt. The bolt is headed at one end as at 15 to prevent the same sliding longitudinally of the barrel. 75

The whip holder for use in connection with a base of the above described character, and indicated generally at 7, comprises an elongated sheet of spring metal bent upon itself to provide a pair of spring jaws 16. These 80 jaws are normally closely related at their free ends, but may be separated to support a whip between same. Each jaw is provided with a central longitudinally extending outwardly pressed portion 17, the latter forming 85 between them engaging or clutch portions to support a whip butt. The bent portion of the holder 7 engages loosely around the protruding end of the bolt 13, and clamp portions 18 are formed upon the jaws adjacent the bending portion thereof for engagement with the opposite jaw to hold same in close engagement with each other. The lower edges of these clamping portions may 90 be curved to conform to the contour of the bolt 13. 95

Removable bolts 19 are extended through the jaws 16 of the holder to maintain the same in proper clamping engagement with a whip contained within the said holder. It 100 is obvious from this construction that whips of various sizes, and constructions may be rigidly secured within the holders, and yet may be readily removed therefrom when desired by disengagement of the bolts 19 from the said jaws.

A nut 20 is threaded upon extremity of the bolt to prevent disengagement of the holder therefrom while a washer 21 encircles the bolt and separates the base member 110 6 from the holder 7. This washer is provided with a radially extending slot or opening as

shown, through which one end of a torsional spring 22 extends, the extremity of said spring engaging through an aperture 23 in one of the leaves of the base 6. This spring 5 encircles that portion of the bolt inclosed by the whip holder, and is fastened at its opposite extremity to one of the clamping portions 18 on the whip holder. The tendency of the spring 22 is to maintain the whip 10 holder in a forward direction, a stop 24 projecting outwardly from one of the leaves 8 limiting the forward movement of the said holder.

A ring 25 is secured in one of the jaws 16 15 adjacent the outer extremity thereof, to which one end of a cord or rope may be fastened, the latter leading to a position convenient to be operated by the driver of the vehicle with which the device is to be used.

As shown in Fig. 1 of the drawings the bolt 13 is inclined upwardly a little at its outer end, the inclination of the bolt projecting the whip holder 7 inwardly, whereby the same will be maintained in proper 25 operating position irrespective of the curvature of the hame to which the base may be fastened.

In operation, a whip is inserted in the holder, and the bolt 19 adjusted to firmly 30 bind the jaws 16 upon the same. The spring 22 maintains the holder with the whip in operating position. When it is desired to lash the animal, the driver pulls upon the cord connected to the whip holder. The 35 whip is immediately swung rearwardly and against the tension of the spring 22 and engages with the body of the animal. The degree of force which the driver desires to impart to the whip will be governed by the 40 amount of pull delivered to the cord. Immediately upon releasing the cord, the holder assumes normal upright position. In this manner it is apparent that blows of light or heavy force may be delivered to 45 the body of the animal with but little exertion and without danger of striking the other horses with which the particular animal may be teamed.

The device is of simple construction, which 50 enables it to be manufactured at extremely low cost and applies to hames of various

sizes, shapes and constructions. It is also apparent that whips of various forms may be held within the holder.

While the above is a description of the 55 preferred embodiment of the invention, it is apparent that various changes in the minor details of construction and arrangement of parts may be resorted to if desired without departing from the spirit of the invention 60 or exceeding the scope of the claims.

What is claimed is:

1. In a device of the class described, a base, a barrel on said base, a whip holder, a bolt extending through said barrel and rotatively supporting said whip holder, a stop on said base, a spring inclosed by said whip holder for normally forcing the latter against the said stop, and a cord attached to said holder, substantially as described. 70

2. In a device of the class described, a base, said base comprising a metallic plate bent upon itself to provide a pair of spaced parallel leaves, the said leaves being provided with registering slots, a barrel on one 75 of said leaves and a shaft in said barrel, a holder on said shaft, means for forcing said holder in one direction, a stop on one of said leaves for limiting the movement of said holder, and a bolt extending through said 80 registering slots for securing said base to a support, substantially as described.

3. In a device of the class described, a base, a shaft extending from said base, a holder comprising a sheet of metal bent upon 85 itself to provide a pair of resilient jaws mounted to rotate upon said shaft, a spring arranged upon said shaft normally forcing the said holder in one direction, a stop on said base for limiting the movement of said holder, the said holder being provided with aligned pressed portions, the said leaves having registered openings, bolts detachably secured in said openings, and a cord attached to said holder substantially as described. 90 95

In testimony whereof I affix my signature in presence of two witnesses.

SAMUEL A. GARBER.
